Patented Apr. 17, 1973

226,716

GAME BOARD INDICATOR DEVICE

Thomas D. Ledgerwood, 823 Mockingbird Lane,
Norman, Okla. 73069

Filed Jan. 25, 1971, Ser. No. 109,753

Term of patent 14 years

Int. Cl. D21—01

U.S. Cl. D34—5

FIG. 1 is a front plan view of the game board indicator design;

FIG. 2 is a rear plan view of the design; and

FIG. 3 is an exploded view in perspective of the game board indicator device design.

I claim:

The ornamental design for a game board indicator device, substantially as shown and described.
